UNITED STATES PATENT OFFICE.

ROBERT F. BERKEBILE, OF KANTNER, PENNSYLVANIA, ASSIGNOR OF ONE-HALF TO
THOMAS J. ADAMS, OF KANTNER, PENNSYLVANIA.

ADVERTISEMENT-HOLDER.

957,539.

Specification of Letters Patent. Patented May 10, 1910.

Application filed February 15, 1909, Serial No. 477,939. Renewed December 16, 1909. Serial No. 533,395.

To all whom it may concern:

Be it known that I, ROBERT F. BERKEBILE, a citizen of the United States, residing at Kantner, in the county of Somerset, 5 State of Pennsylvania, have invented certain new and useful Improvements in Advertisement-Holders; and I do hereby declare the following to be a full, clear, and exact description of the invention, such as 10 will enable others skilled in the art to which it appertains to make and use the same.

The invention relates to a holder and more particularly to the class of advertising holders or receptacles adapted to receive advertising matter for distribution, such as toilet paper, barber's paper, programs, time tables or the like.

The primary object of the invention is the provision of an advertisement holder or 20 receptacle in which the same is provided with one or more transparent faces so that paper or the like having advertising matter thereon will be displayed through the transparent face or faces of the said receptacle as the paper is delivered in single sheets 25 from the holder or receptacle.

Another object of the invention is the provision of an advertisement holder or receptacle which is adapted to receive a 30 package of toilet paper or the like, each sheet of which contains on its front face an advertisement which is adapted to be displayed or visible to a person, and means for automatically feeding the package for 35 wardly within the holder or receptacle so that the sheets of paper may be readily gripped and removed from the holder or receptacle and to enable the forward sheet of the package to be brought into position 40 for displaying the advertising matter thereon.

A still further object of the invention is the provision of a holder or receptacle of this character which is simple in construction, thoroughly efficient in operation, inexpensive in the manufacture and that is 45 practically dust-proof and sanitary.

With these and other objects in view the

invention consists in the construction, combination and arrangement of parts as will be hereinafter more fully described, illustrated in the accompanying drawings which disclose the preferred form of embodiment of the invention and as brought out in the claims hereunto appended. However, it is to be understood that minor changes, variations, and modifications may be made such as come properly within the scope of the claims hereunto appended without departing from the spirit of the invention, or sacrificing any of its advantages.

In the drawings: Figure 1 is a front elevation of the invention. Fig. 2 is a sectional view on the line 2—2 of Fig. 1. Fig. 3 is a front view with the front wall broken away. Fig. 4 is a plan view looking toward the inner face of the removable cover or top. Fig. 5 is a side elevation partly in section. Fig. 6 is a sectional view on the line 6—6 of Fig. 5. Fig. 7 is a detail perspective view of the follower plate.

Similar reference characters indicate corresponding parts throughout the several views in the drawings.

In the drawings, the numeral 10 designates generally the holder which comprises a case having vertical front and rear walls 11 and 12 and vertical side walls 13 and which case has a closed contracted bottom 14 and an open opposite end which latter is closed by a removable cover or top 15, the latter having a suitable opening for accommodating a beveled glass panel 16 the same detachably mounted in the opening in the cover or top by having its beveled edges engaging correspondingly beveled edges of the opening in the top or cover. Immediately below the glass panel is a card 17 which latter has on its outer face suitable advertising matter which is adapted to be displayed through the glass panel 16 so that the advertising matter is visible to a person from the outside of the casing or holder. Pivoted to the inner face of the top or cover 15 are retainer members 18 which latter have

their free ends slotted to be brought into locked engagement with pins 19 depending from the inner face of the cover or top so as to properly hold the card 17 and glass panel 5 16 in proper position in the opening in the cover or top.

Projecting inwardly at the top edge of the side walls 13 and at right angles thereto are short flanges 20 one of which is adapted 10 to be engaged by a recessed block 21 secured to the under face of the cover or top and the other flange adapted to be engaged by a key-operated latch 22 carried by the cover or top so that the latter can be removably se- 15 cured to the casing or cover.

Contained in the front wall 11 of the casing is a suitable opening having beveled edges to engage correspondingly beveled edges of a glass panel 23 which latter is 20 held within the said opening by pivotal retainer members 24 which detachably engage pins 25 projecting inwardly from the front wall of the casing, and they being so placed as not to obstruct the advertisement 25 sheets nor bind said sheets along the sides thereof.

Within the casing and projecting at right angles from the side walls 13 are oppositely disposed supporting ledges 26 which form 30 rests for a package or paper 27 formed of a plurality of sheets each of which has on its front face advertising matter so that the same will be displayed through the glass panel 23 when the package or paper is contained within the casing.

Within the casing 10 below the supporting ledges 26 and disposed transversely in said casing is a removable shaft or pin 28 to which is connected a spring member the 40 same formed of a single strand or wire bent to form a U-shaped yoke 29 and the free ends of the wire are coiled as at 30 about the shaft or pin 28 and have their terminals bearing against the back face of the said 45 casing 10 so as to tension the U-shaped yoke which latter contacts with the rear face of a follower plate 31 which latter is positioned in rear of the package or paper 27 which latter is advanced forwardly in the 50 casing 10 upon the removal of single sheets thereof from the casing. Projecting inwardly from the front wall 11 near its top are a pair of spikes 32 which latter penetrate the sheets of paper as the package of 55 paper is fed forwardly toward the front wall 11 of the casing and which spikes serve to prevent the individual sheets of paper of the package from binding against the front of the casing and also accidentally falling 60 from or out of the casing. The said follower plate 31 contains in opposite faces near opposite edges thereof transverse grooves 33 to permit the spikes to engage the

sheets of paper in a proper manner until all of the sheets have been delivered from the 65 casing.

To permit the delivery of sheets of paper from the package 27 exteriorly of the casing 10 there is provided in the front wall 10 a cutaway portion forming an opening 34 70 which latter intersects a slot contained in the contracted bottom 14 at the point where it meets the lower edge of the front wall of the casing.

It will be seen that when the lower front 75 edge of the package of paper 27 is grasped by the finger or thumb through the opening 34 and pulled downwardly to withdraw a sheet the package of paper will be forced more tightly against the front wall 11 of 80 the casing and as each sheet is delivered from the latter the package of paper is automatically fed forward in said casing upon the advancement of the follower plate through the medium of the tension member 85 and in this manner the advertising matter on each sheet of paper is displayed or visible through the glass panel 23 prior to its removal from the casing.

It is to be understood that the sheets of 90 the package of paper 27 contain advertising matter different from each other so that as the sheets are successively delivered from the casing various reading matter will be displayed through the glass panel of the casing. 95

What is claimed is—

1. A holder of the class described comprising a casing having a transparent front and adapted to receive a package of paper containing advertising matter on each sheet 100 thereof, supporting ledges projecting inwardly from opposite sides of the casing, a follower plate slidably mounted upon said ledges, said casing containing a delivery slot below said transparent front and in advance 105 of the ledges, means within the casing to automatically feed forward the follower plate for advancing the sheets of the package of paper in the path of the slot and also for making visible the advertising 110 matter upon the discharge of individual sheets through the slot, and spurs projecting inwardly from the front of the casing and adapted to engage the forward sheet of a package of paper to suspend said sheet and 115 to prevent its accidental discharge through the slot.

2. In a holder of the class described, the combination with a plurality of sheets of paper having printed matter on each of the 120 same, a casing receiving said sheets of paper and having a delivery slot therein at its front, a transparent panel mounted at the front of the casing to make visible the advertising matter upon the forward sheet of 125 paper within the casing, supporting ledges

within said casing for the paper and terminating at their forward ends in rear of the slot, a follower plate slidable upon said ledges and arranged in rear of the sheets of paper, a spring yoke member acting upon the follower plate to advance the same, and pointed spurs projecting inwardly from the front of the casing and adapted to penetrate the forward sheets of paper when in

the path of the delivery slot to prevent 10 their accidental discharge through the latter.

In testimony whereof, I affix my signature, in presence of two witnesses.

ROBERT F. BERKEBILE.
